UNITED STATES PATENT OFFICE.

EDGAR GUGGENHEIM, OF NEW YORK, N. Y., ASSIGNOR OF ONE-HALF TO MEYER W. SCHLOSS, OF NEW YORK, N. Y.

DISPENSING-RECEPTACLE.

1,670,502

Specification of Letters Patent. Patented Aug. 19, 1913.

Application filed July 27, 1912. Serial No. 711,778.

To all whom it may concern:

Be it known that I, EDGAR GUGGENHEIM, a citizen of the United States, residing at the city of New York, in the borough of Manhattan and State of New York, have invented certain new and useful Improvements in Dispensing-Receptacles, of which the following is a full, clear, and exact description.

10 This invention relates to dispensing receptacles and has particular reference to toilet powder boxes intended to be carried about by ladies on a chatelaine or in a bag, for use whenever required.

15 The object of the invention is to provide a box of this character which will prevent the escape of the powder therefrom when it is closed and from which the powder may be dispensed and used with convenience and 20 facility.

The invention consists of the construction hereinafter described and claimed.

Referring to the drawing, Figure 1 is a 25 vertical central section of my improved box, shown in its closed condition; Fig. 2 is a similar view of the box shown in its open condition; Fig. 3 is a side elevation of the box closed; and Fig. 4 is a vertical section of the box modified in certain details.

30 The box is indicated by the numeral 1, and is preferably of shallow cylindrical form having a bottom 2 in which there may be a filling opening covered by a screw-plate 3, and a top 4. This top is preferably 35 flush with the upper edges of the side walls of the box and is preferably flat as shown. It is provided with perforations 5 through which the powder 6 may be dispensed. Instead of a series of perforations 5, there may 40 be one perforation; as shown at 7 in Fig. 4; this being a matter of choice or depending upon the nature of material to be carried in the box. In any case, however, the top is 45 to be of such form as to furnish a support 50 for the cover as will be hereinafter referred to. The cover of the box is indicated by 8 and consists of a disk-like block of wood, fiber, metal or other suitable material, having a lower face corresponding in diameter 55 to the top 4 of the box. On this lower face of the cover is fixed, by tacks or other suitable means, a pad 9 extending substantially over the entire surface. This pad may be of chamois, felt, or other material commonly used for distributing powder upon the skin.

A handle 10 is provided for manipulating the cover, but this may be substituted by a flange 11, as shown in Fig. 4. The cover with its padded face is intended to effectively close the opening or openings in the top 4 of the box so as to prevent the escape therefrom of the powder, and this is accomplished by holding the cover with its pad under compression against the top so that the flexible pad will be squeezed partially 60 into the perforations. For accomplishing this, I provide the member 12 which is in effect a telescoping sleeve loosely surrounding the side walls of the box so that it may be freely moved up and down, but in order 65 to limit its movement, the lower edge of the sleeve is provided with an inwardly turned flange 13, shown in Figs. 1, 2 and 3 merely as a contraction of the diameter at the edge of the sleeve, and in Fig. 4 as an upset flange 70 13'. To coact with this flange there is provided on the upper edge of the side walls of the box 1 an outwardly projecting flange 14 of similar character, being in Figs. 1, 2 and 3 a mere outward flaring of the upper edge 75 of the side walls, while in Fig. 4 it is an upset flange 14'. The upward movement of the loose sleeve 12 is limited by the engagement of these two flanges, as plainly seen in Figs. 1 and 4. The upper zone of the member 12 is provided in the construction shown in Figs. 1, 2 and 3, with two diametrically 80 arranged bayonet grooves 15, and in the construction shown in Fig. 4, with an internal screw-thread 15'. Since the bayonet 85 groove is inclined and really constitutes part of a thread, I regard such a groove and the threads as the equivalent of each other. To cooperate with the bayonet groove I provide the cover 8 with two pins or lugs 16 diametrically located and projecting radially 90 therefrom. These pins are adapted to enter the vertical parts of the bayonet grooves and then, when the cover is rotated with respect to the sleeve, to travel along the inclined 95 portions of said grooves, in which movement the sleeve is caused to travel axially with respect to the cover. Obviously the same 100 thing takes place when the cover shown in Fig. 4, which is provided with screw-threads 17, corresponding to the threads 15, is 105 screwed into the sleeve.

Fig. 1 shows the receptacle in its closed condition; to open it, the sleeve 12 is grasped in one hand, the cover in the other, and the 110

two parts rotated in a direction to unscrew or separate the sleeve and cover. When this is accomplished, the sleeve will drop down to the position shown in Fig. 2, leaving the top of the box free and unobstructed, whereby after shaking some of the powder through the perforations onto the pad, the same may be distributed over the face of the pad by rubbing and twisting the cover over and across the top of the box, the absence of a downwardly projecting flange on the cover or an upwardly projecting flange on the box permitting this operation. When the powder is thus evenly distributed on the pad, it may be evenly applied to the skin without producing unsightly streaks. It will be seen that with a box having a flange projecting above the perforated top, difficulty would be encountered in getting the puff into the space inclosed by the flange unless the puff and cover were of much less diameter than the flange. Furthermore, it would not be as easy to distribute the powder on the puff if such a flange were present.

To close the box, the sleeve 12 is lifted until the pins 16 or the threads 17 can engage with the grooves or threads 15. Then, by holding the sleeve firmly and rotating the cover, the sleeve will rise upon the cover until the flange on its lower edge engages the flange on the upper edge of the walls of

the box; whereupon, by the continued rotation of the cover with respect to the sleeve, the cover will be caused to travel downward against the top 4 of the box, and by exercising a little force, the padded face of the cover will be compressed so tightly against the perforated top that the escape of powder through the perforations will be impossible.

In the form shown in Fig. 4, the padded face of the cover has a different shape from that shown in Figs. 1 and 2 and may pass some distance through the single perforation in the top of the box to come in contact with a paste or a solid substance used for the toilet, which may be afterward evenly distributed upon the pad by rubbing it over the table-like top 4 as above described.

Having described my invention, I claim:

A dispensing receptacle comprising a box having a perforated top, a flange projecting above said top when the box is closed, a pad-carrying cover for said top normally embraced by said flange, and means whereby the flange can be dropped below the perforated top when the box is opened for use.

In witness whereof, I subscribe my signature, in the presence of two witnesses.

EDGAR GUGGENHEIM.
